MEANS FOR BREAKING ELECTRIC CIRCUITS

Charles Bresson, Villeurbanne, France, assignor to Ateliers de Constructions Electriques de Delle, Paris, France

Application June 6, 1931, Serial No. 542,640
In Germany June 10, 1930

3 Claims. (Cl. 200—147)

In the rare instances where it has been proposed to use the electromagnetic blow out effect for extinguishing the breaking arc of electrical apparatus, between contacts located in a decomposable arc extinguishing fluid such as oil, extinction of the arc is had by rendering said arc unstable by extension between contacts movable widely apart. On the other hand, it has also been proposed to facilitate the rupture of the arc by a multiple number of breaks.

In such apparatus the arc flashes between the contacts and produces in the oil a gaseous sphere surrounding the arc on all sides, the arc is thus developed in a medium which is hardly favourable to rapid extinction.

In accordance with the present invention the blow out displaces the two ends of the arc along arc horns or electrodes in a direction, and at a speed, such that the arc is constantly on the surface of the gaseous bubble in contact with the insulating liquid. The gaseous products form a very extended bubble which presents a large cooling surface.

The applicant has also found that the stretching of the arc beyond a certain length does not increase the rapidity of break, and on the contrary, produces a large development of gas which is prejudicial to the functioning of the apparatus, and to a rational construction of the latter. He consequently advocates the use of uniformly spaced electrodes.

The accompanying drawing illustrates diagrammatically a circuit breaker embodying the invention.

This circuit breaker comprises two conductors 3 and 3' connected to the line and disposed inside the lead-in insulators 4, 4' mounted on the cover 5 of an oil tank 6. In said tank, the oil level is indicated at 7. The lower extremity of the conductors 3 and 3' is immersed in the liquid mass and is connected by means of brackets 8, 8' to the inside turn of coils 19, 19' disposed inside the tank and below the oil level. The outside turn of each of the coils is connected to contacts 10, 10' and to blow-out horns or electrodes 21, 21'. The contacts are each pivoted around an axis 11, 11' and urged thereagainst by springs 12 and 12'. Said contacts are pivoted to the lower portion of levers 13, 13' mounted freely around an axis 14. The upper parts of the levers 13, 13' are connected to the operating axis 15 of the circuit breaker.

The blow-out coils 19, 19' are each wound around a core 20. These coils are vertically disposed and rather elevated, as well as the elec-

trodes 21 and 21', to which electrodes the outside turns of the coils are connected. When the lever 15 is drawn upwards the contacts are separated and each of them touches the upper part of the corresponding electrode. At this time, the magnetic blow-out field of the coils 19 and 19' blows the arc formed between the movable contacts 10, 10' onto the electrodes and then displaces this arc along the electrodes 21, 21', whereby said arc in its totality effectuates a rapid translation movement and is quenched before its roots have reached the lower end of the electrodes.

The magnetic blow-out field of the coils 19 and 19' is automatically increased by an electrodynamic blow out resulting from the fact that the electrodes 21 and 21' constitute together with the arc a loop through which the current flows, and the electro-dynamic effects created by this loop tend to enlarge this loop and thus drive the arc in a downward direction.

As the gases coming from the arc form a bubble which is displaced upwards and as the arc is blown out downwards, the latter is no longer surrounded by a gaseous medium as in known arrangements but is located at the surface of this bubble always in contact with the insulating liquid.

As a general rule it seems indicated to displace the arc in the opposite direction to that of the gases. If for any reason it is desired to impart to the gases a direction other than vertical the electromagnetic blow out should then be opposed to this nonvertical direction. However, it is convenient to note that in certain cases the invention may be realized by displacing the arc in a direction different to that of the gases and not necessarily in the inverse direction of the displacement of the gases. In this latter case it is necessary to give to the blow out coils sufficient power so that the arc will be displaced at a speed such that it may be constantly placed outside the gaseous bubble in contact with the insulating liquid.

The same blow out arrangement shown in the drawing is applicable to fuses in oil. It is sufficient to replace the contacts by a fusible conductor.

Having now particularly described and ascertained the nature of my said invention and in what manner the same is to be performed, I declare that what I claim is:

1. In an electro-magnetic device for blowing in a decomposable arc extinguishing fluid the arc of electrical apparatus, substantially uniformly spaced arc horns or electrodes and means

for blowing the arc along the electrodes the direction of blowing and that of the electrodes being adapted to displace the complete arc in a direction different from that of the escaping gases 5 resulting from the action of the arc on the extinguishing fluid.

2. In an electro-magnetic device for blowing in a decomposable arc extinguishing fluid the arc 10 of electrical apparatus, substantially uniformly spaced arc horns or electrodes and means for blowing the arc along the electrodes the direction of blowing and that of the electrodes being adapted to displace the complete arc in a direction opposite to that of the escaping gases result- 15

ing from the action of the arc on the extinguishing fluid.

3. In oil immersed electric circuit breakers, movable contacts, substantially uniformly spaced electrodes disposed on either side of the contacts, means to separate these contacts and to cause each of them to touch the corresponding electrode and electro-magnetic blow-out means to blow the arc from the spaced contacts to the electrodes and to displace this arc along these electrodes in a direction different from that of the escaping gases resulting from the action of the arc on the oil. 80 85
